UNITED STATES PATENT OFFICE.

EDWARD BOEHM, OF TAMPA, FLORIDA.

REFRIGERATOR AND METHOD OF MANUFACTURING THE SAME.

1,378,003.

Specification of Letters Patent. Patented May 17, 1921.

Application filed March 20, 1920. Serial No. 367,464.

To all whom it may concern:

Be it known that I, EDWARD BOEHM, a citizen of the United States of America, and resident of Tampa, Hillsborough county, 5 and State of Florida, have invented certain new and useful Improvements in and Relating to Refrigerators and Methods of Manufacturing the Same, of which the following is a specification.

10 This invention relates to certain improvements in refrigerator boxes or casings and the like and methods of producing the same; and the objects and nature of the invention will be readily understood by those skilled 15 in the art in the light of the following explanation of the accompanying drawings illustrating what I now believe to be the preferred mechanical expression or embodiment of my invention from among other forms, 20 constructions and arrangements within the spirit and scope thereof, and of the preferred method followed in the production thereof.

An object of the invention is to provide a 25 refrigerator box or casing or the like composed in whole or in part of stoneware or porcelain (so-called) walls built up of assembled ceramic blocks united into a homogeneous or integral mass by fusing suitable 30 intervening material under comparatively high temperature.

And a further object of the invention is to provide a comparatively simple and efficient 35 method for the production of the hereinbefore mentioned product.

With these and other objects in view my invention consists in certain formations, constructions and arrangements and the method of producing the same substantially as hereininafter set forth and specified.

In the accompanying drawings which somewhat diagrammatically illustrate an embodiment of the invention and product of the method,

45 Figure 1 is a front elevation of a box or casing.

Fig. 2 is an edge elevation thereof.

Fig. 3 is a horizontal section, the tiles or blocks being shown in top plan.

50 Fig. 4 is a detail view of one of the stoneware blocks or tiles, partially broken away.

55 My present invention contemplates assembling, fitting and cementing together stoneware (or the like material) blocks (tiles) to form the inclosing walls of a case

or box (such as a refrigerator) and then firing the case or box so constructed, up to the necessary temperature to fuse the cement without breaking down the stoneware 60 blocks, with the end in view of uniting the blocks, through the medium of the fused cement, to form, what in effect will be, a one piece or homogeneous stoneware or porcelain-like structure.

65 I preferably employ individually-finished commercial porcelain or stoneware blocks that in the process of manufacture have been fired or vitrified by a temperature of somewhere about twenty three hundred degrees 70 Fah.

These individually-completed previously finished stoneware blocks are assembled and fitted together to form the desired inclosing structure, preferably embodying bottom, 75 top, and vertical front, back and side walls 1, 1^a, 2, 2^a, and 3. The blocks, when fitted, together, are laid in any so-called putty, mortar or cement suitable for accomplishing the purposes of my invention, i. e. a 80 cement which on drying or setting will hold the blocks together until such cement is fused, and that when fused will serve to unite the blocks to form a one piece or homogeneous porcelain or stoneware mass. 85 I prefer to employ a cement that will fuse at a high temperature but at a temperature lower than the temperature employed in firing the blocks, a temperature slightly lower than the temperature at which said 90 blocks will fuse. For instance, I usually employ a uniting medium (herein termed "a cement") that will fuse at say, approximately nineteen hundred degrees Fah. where the previously finished blocks employed 95 were vitrified at a temperature, say, of about twenty three hundred degrees Fah.

For instance, I can employ a cement composed of say approximately three parts grog (calcined kaolin, ground fine) thoroughly 100 mixed with say about one and one half parts of red lead mixed with sufficient water glass to make the cement of the desired consistency or plasticity. The cement when applied is of approximately the consistency of soft 105 putty so that it can be easily manipulated and spread on the mortar beds of the blocks. This cement on becoming dry or set will bind the blocks together against separation when the structure is being handled preparatory to firing. The structure thus completed and cemented, is then placed in a kiln and fired or 110

exposed to a maximum temperature slightly below the fusing point of the blocks but sufficiently high to fuse the cement or mortar. For instance, the temperature of the kiln is run up to approximately nineteen hundred degrees, Fah. to fuse the particular cement hereinbefore described, but without breaking down the blocks and without reducing the cement to such a degree of fluidity as to permit it to run out of the joints between the blocks. The firing is conducted in such a manner and for such a length of time, that on cooling, the resulting structure is a one piece or homogeneous mass or body of preferably white stoneware.

10 The outer surfaces of the structure can be suitably glazed after the completion of the structure, or the surfaces of the stoneware blocks that are exposed in the completed structure, can be glazed before the blocks are assembled to build up the structure.

20 After completion of the stoneware body, inside partitions and ice supports, and outside doors can be applied and fitted in any suitable manner and by any desirable means.

25 The stoneware blocks or tiles employed in building up the structure can be of any suitable formation and shape. However, I prefer to employ tiles or comparatively thin blocks that will form several insulating air spaces between the inner and outer surfaces of each wall and that will produce imperforate walls without joints between blocks extending completely through the wall from one surface to the other thereof.

30 I also prefer to form each wall of several parallel series or layers of hollow blocks, one layer forming one side or surface of the wall and the other layer forming the other surface or layer of the wall, with the two layers interlocking midway between the opposite sides of the wall, *i. e.*, within the wall.

35 In the particular embodiment illustrated, I show hollow blocks closed at one end a' , and open at the other end, and each having a flat closed outer side wall a to form an area of one side face of a wall of the completed structure; two opposite edge faces b providing cement bed c throughout the lengths of said edge faces and adjoining the face of outer side wall a ; a cement bed formed by the closed end a' of the block, and a cement bed or seat d formed by the edges of the block walls that surround the longitudinal air space e at the open end of the block. The inner or rear side or wall of the block is centrally and longitudinally depressed to form a longitudinal dovetailed or undercut socket or recess h throughout the block length, and 40 two end longitudinally hollow key portions g . In assembling, the blocks of a layer are arranged parallel edge to edge in superimposed courses, with the cement joints i joining the cement beds c of a course. The

45 courses of a layer are arranged so that the joints i are out of alignment with the adjacent courses, and with the edge d of each course fitting the closed ends a' of the blocks of the next course and united by cement joints i . The courses of one layer are interlocked with the previously laid course of the opposite side layer by longitudinally sliding the blocks into place with their key portions occupying the dovetailed sockets of the previously laid course. The blocks of one layer 70 are thus dovetailed to the blocks of the opposite layer against outward or separating movement, and are so arranged that the cement joints i of one layer of blocks are out of alignment with the corresponding joints 75 of the other layer of blocks.

Special forms of angle blocks, such as 8, can be provided at the corners of the box or case to join and lock the vertical walls together. Also, if desired, special forms of 85 blocks, such as 9, can be provided to form door jambs and constitute the same as interlocked parts of the case walls.

The blocks of each layer are cemented together as laid by the cement joints i and 90 these joints seal each layer (before the built up case is fired) and are continuous and preferably air tight, so that after the case has been fired and the cement fused, the layer will be sealed against air and liquid 95 leakage by the continuous lines of fused unions between the edges of the blocks of the layer.

If the expansion of the blocks during the step of firing the case is not sufficient to 100 take care of the expansion of the air within the hollow walls, small air exhaust holes or 105 perforations 11 can be formed in the blocks during the process of making the blocks for escape of air from the wall interiors during the firing of the case. Before the built up 110 case is fired, these small holes can be partially plugged by pieces of the grog-like cement to permit escape of air during the firing step. By the time the cement plugs fuse sufficiently to seal said holes, the excessive air pressure will be relieved. Minus pressure within the hollow walls can thus be attained with the resulting advantage of increased resistance to exchange of heat and 115 cold through the walls.

I do not wish to limit my invention to the employment of hollow interlocking tiles or blocks as I can employ solid earthenware or vitrified blocks of approximately the same 120 interlocking form shown, and I particularly refer to solid blocks of porous or pumice stone-like vitrified material.

The fusible cement can be employed in any desired quantities between the blocks 125 to cover all adjacent or meeting faces and surfaces of the blocks and fill all intervening spaces, or if found more desirable the

cement can be more sparingly employed to close all outside joints at the meeting lines between blocks and between block ends.

It is evident that various changes, modifications and departures might be resorted to without departing from the spirit and scope of my invention and hence I do not wish to limit myself to the exact disclosures hereof.

10 What I claim is:—

1. The method of producing a stoneware body, comprising forming said body by fitting together previously-finished stoneware blocks and sealing the joints between the same by fusible cement in a plastic state, and then firing the body as thus built to fuse the cement and thereby unite the blocks.

2. The method of producing a stoneware body substantially in one piece, which method embodies:—building up said body by an assemblage of previously-vitrified stoneware blocks laid in high fusing point cement, and then firing the body thus built up to a temperature that will fuse said cement without breaking down the blocks.

3. The method of producing a vitrified stoneware body, which comprises building up said body by fitting together stoneware blocks and sealing the joints between said blocks by a cement in a plastic state that fuses at a high temperature, and then exposing said body to a temperature that will fuse said cement without breaking down said blocks.

4. The method of producing vitrified stoneware box-like bodies, consisting essentially in forming a box-like body by fitting together previously finished vitrified blocks and sealing the joints between the blocks with cement that fuses at a temperature lower than the temperature at which the blocks fuse; and then firing said box-like body to a temperature that will fuse the cement, for the purposes substantially as described.

5. The method of producing stoneware bodies, comprising the following steps:—fitting together vitrified blocks to form the body and sealing the joints between the blocks by a cement that will set and temporarily hold the blocks against separation and that will fuse at a high temperature and unite the blocks to form a substantially one piece stoneware body; and then firing said built up body to a temperature that will fuse said cement.

6. The method of producing a stoneware body, which comprises fitting together hollow stoneware blocks to form parallel layers of blocks and interlocking the blocks of adjacent layers and sealing the joints between the blocks of each layer by a high fusing point cement; and then firing the

body thus built up to a temperature that will fuse said cement, substantially as described.

7. The method of producing a stoneware box-like body having hollow insulating walls, which consists in building up the body by fitting together hollow stoneware blocks laid in cement, and then kiln firing the body thus built up to a temperature that will fuse said cement without breaking down the blocks.

8. The method of producing a stoneware body having a wall with interior closed insulating chambers, which consists in forming the body by fitting together hollow stoneware blocks laid in fusible cement and assembled to close the chambers formed by the hollow interiors of the blocks, firing the body thus built up to a temperature to fuse said cement, permitting escape of air from said chambers during firing, and sealing said chambers by fused cement during firing.

9. A stoneware box-like structure having hollow insulating walls and composed of hollow stoneware blocks permanently united by fused cement sealing the joints between the blocks and uniting the blocks into a substantially one-piece structure.

10. A stone ware box-like structure composed of stone ware blocks permanently united by fused cement to form a substantially one-piece structure.

11. A stone ware box-like structure composed of super-imposed courses of hollow stoneware blocks, the blocks of each course interlocking and breaking joints with the blocks of adjacent courses and permanently united with each other and the blocks of adjacent courses by fused cement, to form a substantially one-piece structure.

12. A stone ware box-like structure composed of inner and outer walls of stone ware blocks permanently united by fused cement to form a substantially one-piece structure.

13. A stone ware box-like structure composed of inner and outer walls of hollow stone ware blocks, the blocks of the outer wall interlocking with the blocks of the inner wall and permanently united by fused cement sealing the joints between the blocks to form a substantially one piece structure.

14. A stone ware structure of the character substantially as described, comprising bottom, top, and vertical front, back and side walls, composed of hollow stone ware blocks permanently united by fused cement, and said walls permanently united with each other by fused cement, to form a substantially one-piece structure.

15. A structure of the character substantially as described, composed of finished hollow porcelain, or the like blocks, permanently united by fused cement comprising

three parts "grog" thoroughly mixed with one and one half parts of red lead, mixed with a quantity of water glass.

16. A structure of the character substantially as described, comprising inner and outer walls composed of hollow stoneware blocks united by fused cement, said inner and outer walls so composed, interlocking and permanently united by fused cement
10 sealing all the joints between said walls and the blocks of which they are composed and

uniting said walls into an air tight, substantially one piece stoneware structure.

17. A structure of the character substantially as described, composed of hollow stone 15 stoneware blocks having the air partially exhausted therefrom and sealed by fused cement, and said blocks permanently united by fused cement into a substantially one piece structure.

EDWARD BOEHM.
